LIQUID DISPENSING DEVICE FOR
BOTTLESLeon R. Paul, Brooklyn, N. Y., assignor to Dalynip
Pourer Corp., New York, N. Y., a corporation
of New York

Application May 7, 1935, Serial No. 20,121

8 Claims. (Cl. 215—79)

This invention relates to a liquid dispensing device for bottles, preferably associated with the usual cork or stopper and including means extending through the cork for the escape of the liquid therein and means for venting the bottle or other container, while the cork remains tightly in the neck, until the bottle is emptied of its contents.

The main feature of the present invention 10 comprises a stamped blank of suitable sheet material having opposite ring or wing portions connected by a central connecting web portion, and a shank portion pending therefrom; the blank being subsequently folded on its vertical central 15 line by suitable dies for forming an integral vent tube and for interlocking the ring portions to produce a rigid drum like structure having means for holding side disks of paper, celluloid or other material upon which the character of 20 the contents of the bottle may be printed or otherwise applied.

The object of the invention is to provide a one piece structure as above described for permanent attachment to a pouring tube and its associated 25 bottle stopper.

The companion ring or wing portions of the stamped blank each have central generally circular openings into which project clamping tongues or lugs, those lugs of one ring portion being arranged in relatively staggered relation with the lugs of the opposite ring so that when the blank is folded to position the lugs of one ring are in registration with spaces in the other one, and thus, said lugs may be folded across 35 and clamped under and outward against the outer sides of bezel or channel rings for holding side closure disks.

The dispensing device herein described has an ornamental as well as an attractive appearance 40 and is of stout rigid construction well suited for the purpose intended.

Other features of construction will appear as the following description proceeds.

In the drawing disclosing the invention in detail:

Fig. 1 is a side elevation of the device with portions of the cork or stopper, the pouring tube and the vent tube broken away;

Fig. 2 is a plan view of the single stamped blank of sheet metal to form a unit of the construction;

Fig. 3 shows in side elevation the blank of Fig. 2, folded centrally on its vertical central line, showing the vent tube drawn to shape and the parts of the ring clamped together, including

bezel or channel rings for holding printed or colored disks for closing the sides of the ring structure;

Fig. 4 is an enlarged horizontal sectional view, taken on the line 4—4 of Fig. 1;

Fig. 5 is an enlarged fragmentary section taken on the line 5—5 of Fig. 1, showing a means for permanently attaching the ring part to the pouring tube; and

Fig. 6 is an edge view of a bezel or channel 10 ring.

In describing the construction, I will designate the cork or stopper by the letter C, a pouring or flow tube by P, a vent tube by V, a dust excluding swinging gate by G and a disk or handle 15 part by R.

In carrying out the invention a blank 10, of sheet material, such as thin steel or aluminum, is stamped out to produce opposite ring or wing wall forming portions 11, formed with peripheral 20 spacing and reinforcing flanges 12 turned back upon the circular edges 13 of the wall forming portions as in Fig. 2 and at the right in Fig. 4.

The wall forming portions 11, are cut out centrally to produce central spaces 14, surrounded 25 by inwardly directed circularly spaced lugs or tongues 15 which are arranged in opposite staggered relation when the blank is folded on the fold-line F, in Fig. 2, so that opposite tongues may be folded over into oppositely aligned spaces 30 between the tongues of the other ring and folded or clamped down upon the outer faces of bezel or channel rings 16 placed against the outer faces of the ring wall forming portions 11. The channels 17 of the rings 16, are positioned to receive printed or colored side closures, disks or panels 18, to enhance the appearance of the ring or handle part R of the device which will hereinafter be termed "disk" or "disk part".

Returning now to the metallic sheet blank 40 10; the ring wall forming portions 11, are connected by a cross-web 19 from which extends a shank portion 20 which provides material for the vent tube V.

At opposite sides of the fold lines F, of Fig. 2, 45 in the connecting web portion 19, are a pair of open slits or slots 21, a pair of rivet holes 22, and a pair of vent holes 23.

The base of the shank web 20, is cut a short distance up into the cross-web 19 to provide opposite triangular prongs 24, which when the blank is folded, project through a radial slot 25, formed in a metal cap 26, arranged over the top of the cork or stopper C. Said prongs being spread apart and turned back as at 27, Fig. 1, against 50 55

the inner face of the cap 26, to lock the ring or handle R to the cork, and above this connection, a strap or band 28, having rivet holes to correspond to the rivet holes 22 of the blank 10, has its ends passed through the slots 21, from opposite sides of the pouring tube P, and extended outwardly between the folded blank portions 19, to receive a cross bolt or pin 29.

It will be manifest from the foregoing description that this device is first assembled in two separate units, i. e. the cork and its pouring tube extending entirely therethrough and carrying the swinging gate closure 6 and the metallic crown or cap 26 snugly encircling the top of cork; the second assembled unit comprising the ring and handle portion and the vent tube formed integral with the ring and central wall forming portions of the blank 10; this second unit is shaped to its final form as in Fig. 3, by one or more appropriate stamping and drawing dies to achieve economical production.

The units are finally permanently conjoined by grasping the ring R and forcing the free end of the vent tube downward through an orifice in the cork cap 26 and thence through a registering bore extending through the cork as far as the prongs 24 entering slot 25 of the cork cap will permit, the prongs are then turned outwardly and upwardly against the wall of said cap, after which the strap 28 is passed around the pouring tube and its ends inserted between the folded connecting web portion 19 and secured by the rivet 29, or otherwise, thus providing a secure rigid connection of the pre-assembled units.

An important structural feature of this invention resides in the shape of the blank 10, whereby the vent tube may form an integral part of the ring or handle portion and the means for connecting the ring wall forming portions and channel rings when the blank is folded along its central vertical line.

What I claim is:

1. In a fluid dispensing device, the combination with a bottle stopper and a pouring tube 45 therein, of a pair of contacting disk members having a folded connecting web portion therebetween and a vent tube integral with said folded web connecting portion and extending through said stopper.
- 50 2. In a fluid dispenser the combination with a stopper and a pouring tube passing therethrough, of a disk member and a vent tube formed of a single sheet of metal; the disk member comprising opposed wall forming portion having contacting marginal spacing flanges and radial inwardly directed tongues; and channel rings held in binding face contact with the said opposed wall forming

ing portions by said tongues when bent upon the outer faces of said rings.

3. In a dispensing device, in combination, a cork, a metal cap encircling the upper end portion of the cork, said cap having a central orifice, a smaller orifice and a radial slot; a disk member having projecting folded wall forming portions with integral prong extensions adapted to be passed through said radial slot and clinched backwardly against the wall of the cork cap to interlock the parts and a vent tube formed with the projecting wall forming portions, and passing through the said smaller orifice of the cork cap and through said cork.

4. In combination, a cork, a cap thereon, a tube 15 passing centrally through the cork and cap, a disk member, a vent tube formed therewith, said cap having a radial slot, a doubled metal connecting web projecting from and integral with the material of the disk member, the doubled metal connecting web having aligned slots and aligned bolt holes; aligned prongs located upon said disk member and projecting through said radial slot to be clinched back upon the cork cap; and a strap on said pouring tube having its ends projected 25 through the slots and fastened by a rivet passing through said holes.

5. In combination, a cork; a pouring tube extending therethrough; a disk member; a vent tube integral with the disk member, the vent tube extending through said cork; and means for connecting the disk member to the cork and pouring tube.

6. In combination, a disk member comprising 35 folded connected webbed wings having tongues, channel rings associated with the wings and assembled in intimate relation therewith by said tongues, a vent tube integral with a portion of the webbed material; disks carried by the channel rings for closing the sides of said member; a cork and a pouring tube extending therethrough and means for connecting the disk member and vent tube to the cork and pouring tube.

7. As an article of manufacture a venting structure for a liquid dispensing device for bottles, comprising a unitary structure having a pair of opposed matching disks, a connecting web between said disks, means between said disks for locking them together in matched position, and a venting tube extending beyond the disks, said venting tube being formed in part and integral with said web and venting means in said web portion of said vent.

8. A structure as set forth in claim 7, in which the said webs are provided with locking prongs.

LEON R. PAUL.
